ANKER S. LYHNE, OF BRIDGEPORT, CONNECTICUT.

FLASH-LIGHT.

1,183,310.

Specification of Letters Patent. Patented May 16, 1916.

Application filed April 7, 1915. Serial No. 19,795.

To all whom it may concern:

Be it known that I, ANKER S. LYHNE, a citizen of the United States, residing at Bridgeport, county of Fairfield, State of Connecticut, have invented an Improvement in Flash-Lights, of which the following is a specification.

This invention relates to flashlights, so called, and has for its object to provide a flashlight which shall be compact and relatively small, inexpensive to make so that it may be sold at a relatively low cost, thoroughly practical and durable, and easy and convenient to operate.

15 With these and other objects in view I have devised the simple and novel structure which I will now describe, referring to the accompanying drawing forming a part of this specification and using reference characters to indicate the several parts:

Figure 1 is a view of my novel flashlight partly in elevation and partly in section; Fig. 2 a transverse section on the line 2—2 in Fig. 1, looking in the direction of the arrows; Fig. 3 a longitudinal section of the lower member of the case from a point of view opposite to that in Fig. 1; Fig. 4 a longitudinal section on the line 4—4 in Figs. 1 and 3; Fig. 5 a detail view of the contact strip and the spring detached, illustrating a preferred construction, and Fig. 6 is a perspective of the insulating washer detached.

It is an important feature of my present invention that I provide a metallic case comprising two parts joined together at substantially the mid-length of the case.

10 and 11 denote the parts of the case. Part 10 is a tube open at both ends and provided at each end with a rolled thread, and part 11 is a tube having a closed end indicated by 12, and a rolled thread near its other end adapted to engage the thread upon the inner end of part 10. The essential feature 45 of novelty is that beyond the thread on part 11 I provide a sleeve 13 which just fits within part 10 past the screw thread on said part so that in connecting the parts together the sleeve of part 11 will first pass within part 10 and serve as a guide to retain the two parts in alinement so that when the threads engage, the complete connection of the parts may be effected by rotating one or both of them without danger of an imperfect engagement and injury to the threads.

14 denotes the lamp which is carried in the

usual manner by a reflector 15, the edge of which rests against the end of part 10. The lens 16 rests upon the edge of the reflector and both parts are retained in place by a threaded ring 17 which engages the thread at the outer end of part 10 and is provided with a flange which grips the edge of the lens.

18 denotes a battery having a center contact 19 adapted to engage the center contact of a lamp in the usual manner. The contacts are held in engagement by means of a spring 20 upon which the inner end of the battery rests.

Upon the outer side of part 11 I place a circuit closer comprising a housing 21, a spring controlled contact button 22 and operating means which may be of any ordinary or preferred construction. I preferably use the circuit closing means of my Patent No. 1,122,777, granted Dec. 29, 1914. The case is provided with an opening 23 through which the contact button may pass into engagement with a contact strip 24. Between this strip and the case I place a wider insulating strip 25. The contact strip is riveted or eyeleted to the insulating strip, as at 26, and the insulating strip and the housing are secured respectively to the inner and outer sides of part 11 of the case by rivets or eyelets 27. The contact strip and the spring are both secured, as by a stud 28, to a washer 29 which may or may not be of insulating material. I have shown the parts as secured together by a flat stud which passes through the washer and the strip and is provided with a slot at one end to receive the end of the spring which is secured in place and the parts secured together by heading down the stud.

30 denotes an insulating washer which is preferably cupped, as shown, and lies between washer 29 and the closed end of part 11. In assembling, the lower end of the insulating strip is preferably placed within the flange of washer 30 as clearly shown in Fig. 4.

In order to prevent injury to contact strip 24 should short circuiting or leakage of the battery occur, I preferably reduce the width of insulating strip 25 below the upper end thereof and wrap the contact strip and the insulating strip with insulating material, indicated by 31, as clearly shown in Fig. 5. In practice, the two strips are ordinarily glued or cemented together and the

wrapping extends about both for convenience, the object being to effectually insulate the contact strip and prevent injury thereto should the battery fail to work perfectly.

5 The course of the current is from the battery through the lamp, reflector and case to the circuit closer, then through the contact strip and the spring to the battery.

The operation is the same as with other 10 lamps of this class. The circuit is closed by operation of the circuit closer to produce a flash which continues so long as the circuit remains closed. When the battery is exhausted, the parts of the case are separated, 15 the battery is thrown out and a new one placed in part 11, no adjustment of contacts or of any parts being required.

Having thus described my invention I claim:

20 1. In a flashlight, the combination of a metallic case, a flat contact strip, a washer

in the bottom of said case to which the contact strip is secured, a battery spring secured to the washer and having electrical contact with the contact strip, an insulating strip to which the contact strip is secured and which is secured to the case, and circuit closing means adapted to engage the contact strip.

2. In a flashlight, the combination of a 30 metallic case, a flat contact strip, a washer in the bottom of said case to which the contact strip is secured, a battery spring secured to the washer and having electrical contact with the contact strip, an insulating strip to which the contact strip is secured and which is secured to the case, insulating material wrapped about the contact strip and the insulating strip, and circuit closing means adapted to engage the contact strip. 35

In testimony whereof I affix my signature.
ANKER S. LYHINE.
